UNITED STATES PATENT OFFICE.

CARL T. GROVE, OF GREAT FALLS, MONTANA.

PLOWDISK-SHARPENING MACHINE.

Application filed March 20, 1922. Serial No. 545,373.

To all whom it may concern:

Be it known that I, CARL T. GROVE, a citizen of the United States, residing at Great Falls, in the county of Cascade and State of Montana, have invented a new and useful Plowdisk-Sharpening Machine, of which the following is a specification.

My invention relates to improvements in disk sharpening machines which are operated in conjunction with a rotary grinding wheel; and the objects of my invention are; first, to provide a machine on which plow disks may be placed and sharpened in a relatively short time; second, to afford facilities by means of suitable adjusting blocks which assure the disk being held at the proper angle for correctly beveling the edge; and third, to provide suitable guards to prevent the disk from being ground too deeply in any one place.

I attain the objects by the mechanism illustrated in the accompanying drawing, in which—

Figure 1 is a side view of the entire machine in a vertical position; Fig. 2, an end view of the machine in a vertical position; Fig. 3, a detailed view in perspective of the upper block 1; Fig. 4, an enlarged view of the ratchet plate which is a part of the upper block 1; Fig. 5, a view of the upper side of the middle block 5; Figs. 6 and 7, larger views of the pinion shown in Fig. 5; and Fig. 8, a view in perspective of the guide bracket 13.

Similar numerals refer to similar parts throughout the several views.

In Figure 1 there are shown a grinding wheel and carrier 23 and a plow-disk 24. I do not wish to be limited to any particular type of grinding wheel, as any suitable grinding wheel properly fastened will serve the purpose. Parts 23 and 24 are therefore not claimed as part of my invention.

The device consists of three adjustable blocks, 1, 5, and 8, of which 8 is fastened to a base plank 10 by means of a hinge 9. These blocks 1, 5 and 8 are arranged in a slotted guide bracket 13 (Fig. 8) as shown in the accompanying drawing (Figs. 1 and 2). Block 8 is elevated or lowered to the desired position and firmly fastened in such position by means of a thrubolt which passes through block 8 and the slots in 13, by tightening the wing-nut 14.

Block 5 is pivotally fastened to the upper

side of block 8 by mean of a metal strap 11, firmly bolted to block 8 by thrubolts 12, 12, so that block 5 may be inclined to the desired pitch by being turned on the metal pivot 7. Such tilting of block 5 is accomplished by means of the crank shaft or rod 6 which passes through block 5 and is firmly fastened to block 5 by means of a washer 25 and a taper pin 26 on the upper and the under side of block 5 as shown on the drawing (Fig. 1). The crank shaft 6 passes on down through block 8 and through the nut 15, which nut is countersunk on the under side of block 8 and is held in place by the metal plate 16.

Block 1 is slidably fastened to the upper side of block 5 by means of the thrubolt 2, the head of which is countersunk in the under side of block 5 and the shank of which passes up through the slot A—A in block 1 (Fig. 3). When block 1 has been moved forward or backward to the proper position, it is firmly clamped in place by tightening the wing-nut 3, which rests on the washer 4. To facilitate such sliding forward or backward of block 1, there is placed on the under side of block 1 a ratchet plate 18 (Fig. 3 and Fig. 4). This ratchet plate 18 is to receive the teeth of the pinion 17 (Figs. 2, 5, 6, and 7). Piece number 7 serves the double purpose of a pivot upon which block 5 may be tilted and also of a pinion crank for turning the pinion 17. The said pinion 17 is located in a notch rabbeted out of the upper side of block 5, is firmly fastened to the pinion crank 7 by means of a set screw, and is so placed that the teeth of the pinion will be received by the ratchet plate 18. Thus when the pinion crank 7 is turned, block 1 will slide forward or backward to the desired position.

A metal bracket 19 is placed on each side of the grinding wheel close to the point of contact with the disk. The upper section of each of these two brackets 19, 19, is drilled and tapped to receive the guard screw 20, the shank of which extends out beyond the rim of the grinding wheel and, by pressing against the disk, prevents a deeper cut than might otherwise be made. The two guard screws 20, 20, are firmly fastened at the proper distances by means of a lock nut 21 on each.

A metal trough 22, which is riveted or bolted on to the guard bracket 19, receives

the grindings and carries them over the side of the base plank 10.

The device is operated in the following manner: The plow-disk is placed on the metal holder 27 with the edge against the grinding wheel on a line horizontal with the center of the grinding wheel's shaft. This placing the edge of the disk on a line horizontal with the center of the grinding wheel's shaft is done by raising or lowering the hinged block 8. The heel of the disk is ground down until it comes close to the cutting edge—but not further. The thumb guard-screws 20, 20 are set against the disk on both sides of the grinding wheel and lock nuts 21, 21 are tightened. In this position the first round of grinding is completed by revolving the disk. When this is completed, without removing the disk, block 1 is elevated a trifle if necessary, which is accomplished by loosening wing-nut 3 and turning the pinion crank 7. Wing nut 3 is retightened and block 5 is tilted by turning the crank shaft 6 so that the grinding wheel will cut the heel of the new grinding. The disk is revolved as before. If a third grinding is desired, the disk may be reset in the same manner as for the second round of grinding.

I am aware that prior to my invention disk sharpening machines have been made and marketed. I therefore do not claim

such a combination or machine broadly; but

I claim:

1. A work holder for cultivator disks while being ground, consisting of an upper block having a pin capable of acting as a pivot for the disk, a base, a lower block pivoted to the base, a middle block pivoted to the lower block and upon which the upper block is mounted to slide, and a guide bracket and straps for holding the blocks in place. 35

2. A work holder for cultivator disks while being ground, consisting of an upper block having a pin capable of acting as a pivot for the disk, a base, a lower block pivoted to the base, a middle block pivoted to the lower block and upon which the upper block is mounted to slide, and a guide bracket and straps for holding the blocks in place, and means carried by the middle block for causing it to tilt on the lower block. 45

3. A work holder for cultivator disks while being ground, consisting of an upper block having a pin capable of acting as a pivot for the disk, a base, a lower block pivoted to the base, a middle block pivoted to the lower block and upon which the upper block is mounted to slide, and a guide bracket and straps for holding the blocks in place, and means for causing the upper block to slide upon the middle block. 55 60

CARL T. GROVE.
